CLAIM

The ornamental design for a visual information terminal, as shown and described.

DESCRIPTION

FIG. 1 is a front top perspective view of a visual information terminal showing my new design;

FIG. 2 is a front elevational view thereof;

FIG. 3 is a top plan view thereof;

FIG. 4 is a left side elevational view thereof; and,

FIG. 5 is a right side elevational view thereof.

The rear is not considered to be part of my claimed design.
